UNITED STATES PATENT OFFICE.

HARRY MCLOUGHLIN, OF STAPLETON, NEW YORK, ASSIGNOR TO BARTON E. KINGMAN, OF NEW YORK, N. Y.

RAILWAY-CAR.

SPECIFICATION forming part of Letters Patent No. 699,340, dated May 6, 1902.

Application filed August 31, 1901. Serial No. 73,983. (No model.)

To all whom it may concern:

Be it known that I, HARRY MCLOUGHLIN, a citizen of the United States, residing at Stapleton, Staten Island, in the county of Richmond and State of New York, have invented new and useful Improvements in Railway-Cars, of which the following is a specification.

This invention relates to railway-cars, and especially to that class of cars the frames of 10 the bodies of which consist of metallic tubular structures to which the sides and ends and the roof and floor of the car-body are fastened; and it has for its object to construct a car of 15 the character referred to in such novel manner as to combine strength, durability, and safety with reduction in weight of the car and the cost of its manufacture.

It also has for its object to so construct the car that the rivets, bolts, or other fastenings 20 employed to secure the parts together will be wholly concealed from view and a rich, handsome, and finished appearance imparted to the car.

To these ends my invention consists in the 25 features and in the construction, combination, and arrangement of parts hereinafter described, and particularly pointed out in the claims following the description, reference being had to the accompanying drawings, 30 forming a part of this specification, wherein—

Figure 1 is a view in side elevation of my improved car. Fig. 2 is a view in end elevation thereof, partly in section. Fig. 3 is a top plan view illustrating one of the corner-brackets 35 for coupling together two adjacent side and end tubular sections. Fig. 4 is a similar view showing one of the corner-brackets for coupling together the ends of the side and end sills. Fig. 5 is a detail horizontal sectional view illustrating one of the corner-posts, stringers, and 40 standards, and the panels riveted thereto. Fig. 6 is a detail perspective view of a portion of one of the stringers. Fig. 7 is a similar view of a portion of one of the corner-posts. Fig. 8 is a detail perspective view showing the 45 manner of connecting the corner-posts and side and end sills. Fig. 9 is a detail perspective view of a portion of one of the standards. Fig. 10 is a similar view of one of the brackets employed for securing the standards to

the sills; and Fig. 11 is a similar view showing the means for connecting the upper ends of the standards, roof-beams, and the upper sectional tubes. Fig. 12 is a bottom plan view of the car-bottom, illustrating additional 55 means for imparting stiffness and strength to the framing.

In constructing my improved car I first construct a metallic tubular frame of the general shape of the body of the car and comprising 60 vertical corner-posts and intermediate standards and horizontal stringers, sills, and connected tubular sections or sectional stringers, and to such frame I rigidly attach the side and end panels and the roofing and flooring. 65

In the drawings I have shown by way of example a railway passenger-car; but it will be obvious that the same principles and features of construction may be employed in constructing express, mail, baggage, freight, and 70 various different kinds or types of cars.

Referring to the drawings, the numeral 1 indicates the corner-posts of the frame; 2, the posts of the door-frames; 3 and 4, the horizontal stringers; 5, the standards or uprights; 6 and 7, the tubular sectional stringers; 8, the longitudinal sills; 9, the transverse end sills; 75 11 and 12, respectively, the panels forming the sides and ends of the car-body, and 13 and 14, the flooring and roof of the car. 80

The base or bottom of the car consists of the longitudinal sills 8 and the transverse end sills 9, each consisting of a tube of steel or other suitable metal pressed, rolled, or drawn into the shape in cross-section most clearly 85 shown in Fig. 2 of the drawings, whereby each of said tubes has two straight and flat faces 13 and 14, disposed at a right angle to each other, and an inner and under concavo-convex wall 15. As shown most clearly in 90 Fig. 2 of the drawings, the longitudinal sills are arranged parallel to one another at each side of the bottom of the car-body, the faces 13 being disposed horizontally and the faces 14 being arranged vertically and outermost, 95 the concavo-convex walls 15 being disposed inwardly or toward one another. The transverse sills 9 are arranged at right angles to the ends of the side sills and consist of tubes constructed precisely like the tubes 8. The 100

side and end sills are connected together at their ends by corner-brackets constructed as follows:

Referring to Fig. 4, the numeral 16 indicates the body of the bracket, consisting of a casting, or it may be of pressed metal having the general shape of a "bend" or "elbow," the members of which are disposed at a right angle to one another and having intermediate rounded corners 17, the said elbow corresponding in shape in cross-section to the cross-sectional shape of the sills. Each of the members of the elbow is provided with an integral projecting tenon 18, that is of the same shape in cross-section as the sills and of such size as to be inserted and fit in the end of the adjacent hollow tube or sill 8 or 9, as the case may be. The brackets are arranged at the corners or meeting ends of the side and end sills, the tenons fitting in the ends of the sills and rigidly fastened therein in any suitable manner—as, for example, by riveting, as indicated at 19. Formed integrally with the elbow or bracket 16 and projecting horizontally inward from the inner angle of the same is a lug or shelf 20, having a flat upper face 21 lying in the same horizontal plane with the upper flat face 13 of the bracket, and said lug or shelf is perforated, as at 21', for the purpose presently made apparent. As shown most clearly in Fig. 4 of the drawings, the body 16 of the bracket is provided with shoulders 22, and when the tenons 18 are fitted in the ends of the sills 8 and 9 the outer faces of said body lie flush with and form a continuation of the outer faces of the said sills.

The corner-posts 1 each consist of a tube of steel or other suitable metal pressed, rolled, or drawn into the shape in cross-section most clearly shown in Fig. 5 of the drawings, whereby said tube has two flat straight vertical outer sides or faces 23, united by a rounded intermediate portion or corner 24 and an inner concavo-convex wall 25, terminating at its ends in flat or straight portions 26, the ends of the flat outer portions 23 being rounded, as at 27, till they meet or join the flat ends 26 of the inner concavo-convex wall 25.

The corner-posts 1 are arranged vertically above the four corners or corner-brackets of the sills and are attached to the latter by brackets, constructed as follows: The numeral 28 indicates a bend or elbow consisting of two members disposed at a right angle to one another and united by a rounded intermediate portion or corner 29, the ends of the two members terminating in tenons 30. Projecting horizontally and inwardly from the inner angle of the elbow is a lug or foot 31, having a flat under side and provided with perforations 32. Formed on the upper side of the elbow 28 is a vertical tenon 33, having the same shape in cross-section and adapted to fit within the lower end of the corner-post 1, to which it is rigidly secured by any suitable fastenings—as, for example, by rivets 34.

The brackets 16 and 28 are cast or pressed

hollow for the sake of strength and lightness, and the brackets 28 rest on the brackets 16 and are rigidly secured to the latter by rivets 70 35, which pass through the perforations in the lugs 20 and feet 31. The body of each bracket 28 is shouldered, as at 36, whereby the faces of the corner-post coincide or lie flush with the body of the bracket. 75

The horizontal stringers 3 and 4 each consist of a tube of steel or other suitable metal pressed, rolled, or drawn into the shape in cross-section most clearly illustrated in Fig. 6 of the drawings, whereby said tube has a flat vertical inner face 39 and a convex, rounded, or bead-like outer face 40, constituting an ornamental molding. Said stringers extend continuously along the sides and portions of the ends of the car, intermediate the top and bottom of the latter, and at those points where the stringers extend around the corner-posts the inner portions of the tubes 3 and 4 are cut away or removed, as at 41, to form recesses for the reception of the corner-posts. The recesses 41 are of such size and shape that the corner-posts will neatly fit therein and completely fill said recesses, the outer faces or walls 40 of the stringer-tubes being bent around and into close contact with the outer faces of the corner-posts and extend to the posts 2 of the door-frames in the ends of the car, to which they are rigidly fastened, as by riveting. In cutting the recesses 41 in the stringer-tubes tongues 42 are left remaining on the ends of the top and bottom edges or walls of said tubes on each side of the recesses, and these tongues are bent at right angles to the tubes and are fastened to the corner-posts 1 by rivets 43. The stringer-tubes are provided on their inner flat sides or faces 39 with apertures 43, and the inner concave sides 25 of the corner-posts are correspondingly apertured, as at 44, said apertures being formed for the purpose of giving access to the interior of said tubes, so that the rivets may be inserted in place and riveting-tools introduced to rivet down the heads of the rivets. 100

Arranged at suitable and uniform intervals on each side of the car-frame between the corner-posts are intermediate upright standards 45, each consisting of a metallic tube pressed, rolled, or drawn into a shape in cross-section corresponding in shape to the stringer-tubes, and the inner walls or sides of the latter are cut away or removed to form recesses 46, said recesses being of a size and shape to permit the standards to fit therein or pass therethrough, the standards neatly fitting said recesses and completely filling them. The standards are fastened by rivets 47 to tongues 42, struck up from the stringer-tubes in the manner before described, and are provided on their inner flat faces with apertures 48 to permit of the insertion of riveting-tools. As most clearly shown in Fig. 9 of the drawings, the inner flat faces of the stringers and standards lie flush with one another, as do also the 110 115 120 125 130

inner flat faces of the stringers and the flat ends of the curved inner walls 25 of the corner-posts for the purpose hereinafter made apparent. The upper and lower ends of the 5 standards are connected together by sectional tubular stringers consisting of metallic tubes 6 and 7 of the same shape in cross-section as the stringers and standards, there being one such tubular section arranged between every 10 two standards and between the end standards and corner-posts. The tubular sections 6 and the lower ends of the standards are connected together by brackets, the body 49 of each bracket being of the same shape and size in 15 cross-section as the sectional tubes 6 and standards 45, the ends of the body terminating in tenons 50, shaped to fit in the ends of adjacent tubular sections 6, to which they are rigidly fastened by brazing, riveting, welding, 20 or the like. On the upper side of each bracket 49 is formed a vertical tenon 51, that fits in the lower end of the adjacent standard and is fastened therein in the same manner as the tenons 50. On the inner side of each 25 bracket 49 is formed a horizontally and inwardly projecting lug or flange 52, having a flat under side that rests on the upper flat side 13 of the side sill and is rigidly fastened thereto by rivets 53, apertures 54 being formed 30 in the concave inner walls 15 of the sills for the insertion of the riveting-tools. The upper ends of the standards and the sectional tubes 7 are fastened together by brackets 55, provided at their ends with tenons 56 in manner 35 similar to the brackets 49, before described, which fit into the ends of adjacent tubular sections 7, and said brackets are provided on their inner sides with tenons 57, that are bent or deflected slightly upward, as 40 shown, to fit into the ends of the tubular roof-beams 58. The roof-beams 58 comprise metallic tubes of any suitable shape in cross-section and slightly arched, as shown in Fig. 2 of the drawings, and extend inward from the upper 45 ends of the standards to points intermediate the sides and longitudinal center of the car. Between the ends of each two adjacent tubes or beams 58 on either side of the car are disposed longitudinally tubular sections 59, consisting of metallic tubes pressed, rolled, or drawn into the shape best shown in Fig. 2 of the drawings, whereby each of said tubular sections has two flat walls or faces 60, disposed at an angle to one another, and a curved inner wall or face 61. The ends of the tubes 55 59 and roof-beams 58 are rigidly fastened together by brackets 62, provided with tenons 63, that fit into the inner ends of the roof-beams, and with oppositely-projecting tenons 64, that fit into the ends of the adjacent tubular sections 59. Said brackets are also provided with upwardly-projecting tenons 64', that fit into the lower ends of short tubular uprights 65. Between the upper ends of the adjacent uprights 65 are disposed longitudinal tubular sections 66, each consisting of a metallic tube having two flat outer faces 67, dis- 60 posed at an angle to one another, and an inner curved wall or face 68. The tubular sections 66 and uprights 65 are rigidly fastened 70 together by brackets 69, having depending tenons 70, that fit in the upper ends of the uprights, laterally-projecting tenons 71, that fit in the ends of adjacent tubular sections 66, and inwardly and slightly upwardly projecting tenons 72, that fit in the opposite ends of the upper central roof-beams 73, that consist of metallic tubes of any suitable shape in cross-section. The tenons and ends of the several tubes above described are fastened 80 together, as by riveting or in other suitable manner, and the faces of the tubes and connecting-brackets lie flush with one another, in the manner hereinbefore explained. The end roof-beams 58^a are continuous and have 85 suitably secured to them, as by riveting, brazing, or the like, the upper ends of the door-posts 2. The lower ends of the door-posts are secured to the inner adjacent ends of the tubular end sections 6^a and to the end sills by 90 brackets 74, similar in every respect to the brackets 49 before described, excepting that they are each provided with but one laterally-projecting tenon 50. The lower ends of the door-posts fit over the vertical tenons 51 of 95 the brackets 74, and the inner ends of the tubular sections 6^a fit over the tenons 51 of said brackets. The feet or flanges 52 of the said brackets are riveted to the end sills in the same manner as the brackets 49. In all the 100 tubes above referred to apertures are formed in their inner sides wherever they become necessary for the insertion of rivets or riveting-tools, as hereinbefore explained, and all the coupling-brackets are preferably made 105 hollow for the sake of lightness and strength. 110

Against the inner flat walls or faces of the stringers, sectional tubes, and standards, and against the inner flat ends 27 of the corner-posts and the flat inner sides of the door-posts are fitted panels 75, consisting of flat sheets of metal or other suitable material, which are riveted to the flat sides of the several tubes by rivets 76, apertures 44, 48, and 77 being cut in the inner sides of said tubes wherever 115 necessary to insert the rivets or riveting-tools. Metallic tubular window-frames 78 are in like manner fitted and fastened to the stringers 3 and 4, and panels or transparent panes 79 are also fitted between the upper ends of the 120 standards 6 and the stringers 3 and the upper sectional tubes 7. Roofing 80 is fastened to the roofing-tubes and beams, and flooring 81 is laid on and secured to the sills. 125

The bottom of the car is stiffened and braced in the following manner: Extending centrally and longitudinally beneath the bottom of the car is a truss 82, consisting of a hollow tubular beam comprising an upper metallic plate 83, provided on its opposite edges 130 with depending flanges 84, to which are riveted metallic vertical side plates 85, provided at their lower edges with lateral outwardly-projecting flanges 86, and to the underside of

the latter is riveted à skeleton frame or plate 87. Riveted to the outer sides of the plates 85 are sockets 88, in which are fitted and riveted or otherwise suitably fastened brace rods 5 or tubes 89, the outer ends of said braces being fitted and fastened in sockets 90, riveted to the inner sides of the vertical faces 14 of the side sills, apertures 91 being formed in the inner concave walls of said sills to permit of the insertion and fastening of the sockets and for the passage of the braces. Longitudinal tie rods or tubes 92 are attached to the side sills, the ends of said rods or tubes passing through eyes 93, secured to the under sides of the side sills and having screwed over said rods nuts 94, by which said rods or tubes may be strained. Stretchers or spreaders 95 are interposed between said rods or tubes and the bottom of the side sills and are 20 bolted to the latter.

As an additional means for imparting stiffness and strength to the bottom framing of the car I employ braces 96, (see Fig. 12,) each consisting of a metallic T-beam, said 25 braces being arranged in alined pairs, as shown, the inner or adjacent ends of said beams being rigidly fastened to the truss 82 by angle-brackets 97, riveted to the sides of the truss and to the ends of the vertical webs 30 of the beams, and the outer ends of said beams are in like manner fastened to the inner sides of the vertical faces 14 of the side sills 8, apertures being formed in the concave walls of said sills to permit of the insertion and fastening of the angle-brackets and for the passage of the beams in the same manner as that 35 previously described for securing in place the rods or tubes 89. The said T-beams are arranged at points where the wheel-trucks 40 are in practice attached to the car and where the supports 93 for the tie-rods are secured for the purpose of giving additional strength and rigidity to the bottom frame of the car.

By means of my invention I am enabled to 45 construct the frame and body of the car entirely of metal, the frame being tubular throughout. A car thus constructed possesses great strength and at the same is lighter than a wooden car, cannot be telescoped, 50 avoids the danger from splinters and fire in case of accident, presents a rich, finished, and ornamental appearance, and can be manufactured at a relatively small cost. As stated in the first part of the specification, I do not 55 limit myself to the construction of passenger-cars alone, the invention being equally applicable to the construction of various other types of cars.

Having described my invention, what I 60 claim is—

1. A frame for railway-cars, comprising vertical metallic tubular corner-posts and horizontal metallic tubular stringers, said tubular stringers being recessed on their inner 65 sides to fit the corner-posts and bent around the latter, substantially as described.

2. A frame for railway-cars, comprising

vertical metallic tubular corner-posts and horizontal metallic tubular stringers, said tubular stringers being recessed on their inner 70 sides to fit the corner-posts and bent around the outer faces of the latter, the corner-posts and stringers being riveted together, substantially as described.

3. A frame for railway-cars, comprising 75 vertical metallic tubular corner-posts and horizontal metallic tubular stringers, said tubular stringers being recessed on their inner sides to fit the corner-posts and bent around the outer faces of the latter, the corner-posts 80 and stringers being riveted together, and the inner sides of the said corner-posts being apertured on their inner sides for the insertion of riveting-tools, substantially as described.

4. A frame for railway-cars, comprising 85 vertical metallic tubular corner-posts and horizontal metallic tubular stringers, said tubular stringers being recessed on their inner sides to fit the corner-posts and bent around the outer faces of the latter, the ends of the 90 recessed portions of the stringers being provided with tongues or flanges struck up from the walls of the stringers and riveted to the corner-posts, said corner-posts being apertured on their inner sides for the insertion of 95 riveting-tools, substantially as described.

5. A frame for railway-cars, comprising vertical corner-posts consisting of metallic tubes each having two outer flat faces disposed at a right angle to one another and 100 united by a rounded corner, and an inner concavo-convex wall having flat edge portions, the edges of the flat outer faces being rounded and joined to the flat edge portions of the inner wall, and horizontal stringers consisting of metallic tubes having inner flat 105 faces and outer rounded faces, the inner sides of the stringers being recessed to fit the corner-posts and bent around the outer faces of the latter, and said stringers and corner-posts 110 being riveted together, substantially as described.

6. A frame for railway-cars, comprising vertical metallic tubular corner-posts, intermediate metallic tubular standards, and horizontal metallic tubular stringers, said tubular stringers being recessed on their inner 115 sides to fit the corner-posts and standards and riveted to said corner-posts and standards, substantially as described.

7. A frame for railway-cars, comprising vertical metallic tubular corner-posts, intermediate metallic tubular standards, and horizontal metallic tubular stringers, said tubular stringers being recessed on their inner 125 sides to fit the corner-posts and standards and riveted to said corner-posts and standards, the inner sides of the corner-posts and standards being apertured for the insertion of riveting-tools, substantially as described.

8. A frame for railway-cars, comprising vertical metallic tubular corner-posts, intermediate metallic tubular standards, and horizontal metallic tubular stringers recessed on 130

their inner sides to fit the corner-posts and standards, the ends of the recessed portions of the stringers being provided with integral tongues or flanges struck up from the stringers and riveted to the corner-posts and standards, said corner-posts and standards being apertured on their inner sides for the insertion of riveting-tools, substantially as described.

10 9. A frame for railway-cars, comprising vertical metallic tubular corner-posts, intermediate metallic tubular standards, and horizontal metallic tubular stringers recessed on their inner sides to fit the corner-posts and standards and riveted to said corner-posts and standards, and tubular sections fitted between the ends of adjacent standards and fastened to the latter, substantially as described.

15 10. A frame for railway-cars, comprising vertical metallic corner-posts, intermediate metallic tubular standards, and horizontal metallic tubular stringers, said standards and stringers consisting of metallic tubes each having a flat inner face or wall and a rounded outer face or wall, the stringers being recessed on their inner sides to fit the standards and corner-posts and riveted thereto, the flat sides of the stringers and standards lying flush with one another, substantially as described.

20 11. A frame for railway-cars, comprising vertical metallic corner-posts, intermediate metallic tubular standards, and horizontal metallic tubular stringers, said tubes being provided with flat inner portions lying flush with one another and riveted together, and panels fitted against said flat portions of the corner-posts, standards and stringers and riveted thereto, substantially as described.

25 12. A frame for railway-cars, comprising vertical metallic corner-posts, intermediate metallic tubular standards, horizontal metallic tubular stringers, and tubular sections fitted between the ends of the standards, said stringers being recessed on their inner sides to fit the standards and corner-posts and riveted thereto, said tubes having flat inner portions lying flush with one another, and panels fitted against said flat portions of the tubes and riveted thereto, substantially as described.

30 13. A frame for railway-cars, comprising vertical metallic corner-posts, intermediate metallic tubular standards, horizontal metallic tubular stringers, and metallic tubular sections arranged between the ends of the standards, brackets interposed between the adjacent ends of the standards and tubular sections and lying flush therewith, said brackets each having two lateral tenons fitted in the ends of adjacent tubular sections and a vertical tenon fitted in the end of an adjacent standard, and panels secured to the inner sides of the corner-posts, standards, stringers and tubular sections, substantially as described.

35 14. A metallic frame for railway-cars, comprising tubular sills, vertical tubular corner-

posts rigidly fastened at their lower ends to the sills, intermediate tubular standards, horizontal tubular stringers fastened to the corner-posts and standards, tubular sections arranged between the lower ends of the standards, brackets arranged between the contiguous ends of the tubular sections and standards and lying flush therewith, each of said brackets having two lateral tenons fitted in the ends of the adjacent tubular sections and a vertical tenon fitted in the lower end of the adjacent standard, and a lug or foot projecting horizontally inward from the bracket and bolted to the adjacent sill, substantially as described.

40 15. A metallic frame for railway-cars, comprising tubular side and end sills rigidly secured together at their meeting ends and each consisting of a metallic tube having a flat horizontal and a flat vertical face or wall and a concavo-convex inner face or wall, vertical tubular standards, horizontal tubular stringers fastened to the standards, tubular sections arranged between the lower ends of the standards, brackets arranged between the contiguous ends of the standards and tubular sections and lying flush therewith, each of said brackets having two lateral tenons fitted in the ends of the adjacent tubular sections and a vertical tenon fitted in the lower end of the adjacent standard, and a lug or foot projecting horizontally inward from the bracket and resting on and riveted to the upper flat face of the adjacent sill, the inner face of the sills being apertured for the insertion of riveting-tools, substantially as described.

45 16. A metallic frame for railway-cars, comprising side and end sills each consisting of a metallic tube having a flat horizontal and a flat vertical face or wall and a concavo-convex inner wall, corner-brackets fitted between the contiguous ends of the sills and each consisting of an elbow having lateral tenons arranged at a right angle to one another and fitted in the contiguous ends of the sills, horizontal lugs or flanges projecting inwardly from the brackets, tubular corner-posts riveted to the said lugs or flanges and horizontal stringers fastened to the corner-posts, substantially as described.

50 17. A metallic frame for railway-cars, comprising side and end sills each consisting of a metallic tube having a flat horizontal and a flat vertical face or wall and a concavo-convex inner wall, corner-brackets fitted between the contiguous ends of the sills and each consisting of an elbow having lateral tenons arranged at a right angle to one another and fitted in the contiguous ends of the sills and provided with a horizontal inwardly-projecting lug or flange, vertical standards secured to the sills, horizontal stringers fastened to the standards, tubular sections fitted between the lower ends of the standards and secured thereto, vertical tubular corner-posts disposed above said brackets, brackets provided

with lateral tenons fitted in the ends of adjacent tubular sections and with vertical tenons fitted in the lower ends of the corner-posts, and having horizontal inwardly-projecting lugs or feet riveted to the lugs or flanges of the corner-brackets, uniting the sills, substantially as described.

18. A metallic frame for railway-cars, comprising vertical tubular standards, horizontal tubular stringers recessed on their inner sides to fit the standards and riveted thereto, and tubular sections arranged between the ends of the standards and connected thereto, panels fitted and riveted to the inner sides of the tubular standards, stringers and tubular sections, said tubes being apertured on their inner sides for the insertion of riveting-tools, substantially as described.

19. A metallic frame for railway-cars, comprising tubular side and end sills rigidly secured together at the corners, a central longitudinal truss consisting of a hollow tubular truss-beam provided on its opposite vertical sides with sockets, and brace-rods fitted at their inner ends to said sockets and connected

at their outer ends to the side sills, substantially as described.

20. A metallic frame for railway-cars, comprising tubular side and end sills rigidly connected together at the corners, a central longitudinal truss consisting of top and side plates and a bottom frame fastened together to form a hollow truss-beam, sockets attached to the opposite vertical sides of the truss-beam and to the interior of the tubular side sills, and brace-rods fitted at their opposite ends respectively to the sockets on the truss-beam and the sockets in the said sills, said side sills being apertured on their inner sides for the passage of the brace-rods and for the insertion and attachment of the sockets, substantially as described.

In testimony whereof I have hereunto set my hand in presence of two subscribing witnesses.

HARRY McLOUGHLIN.
